UNITED STATES PATENT OFFICE

2,099,075

TOY BUILDING CONSTRUCTION

Nils I. Paulson, Chicago, Ill., assignor to Halsam Products Company, Chicago, Ill., a corporation of Illinois

Application May 13, 1936, Serial No. 79,557

10 Claims. (CL 46—26)

My invention relates to toy building construction comprising blocks, strips and locking pieces, and it has for its object the provision of a new and improved form and arrangement of cooperating parts of this type whereby a supply of such parts may be readily and easily built up in association with each other for providing a wide variety of toy buildings and other structures.

It is another object of my invention to arrange the parts in such cooperating form as to enable me to lock the parts very firmly in engagement with each other by the use of locking tabs which are very simple in their form and arrangement so as to be capable of being produced very cheaply without the use of complicated machinery. It is one of the objects of my invention to provide an arrangement of this type in which the locking may be effected by means of straight locking tabs fitted in grooves which are so easily produced in the blocks and strips as to make it practical to produce a complete quota of such locking grooves in each piece even though only a small proportion may be used for any given building operation, such grooves being located in such positions on the blocks and strips as to be covered and hidden in large part by the adjacent blocks or strips.

It is another object of my invention to provide a set of cooperating blocks of this type of different lengths each having a definite relationship to the length of the other blocks, with the lengths of the several blocks preferably having a definite relationship to the thickness of the wall formed by the blocks, and with the blocks or other parts representing doors and windows of corresponding effective lengths along the wall and of an effective size vertically to correspond to the height of two or more tiers of the blocks forming the wall, whereby I may be enabled to vary the construction and the arrangement of the parts through a very wide range for building up any given size and shape of wall by different combinations of parts. In this improved arrangement, a predetermined unit of length corresponding preferably to the thickness of the wall is employed, the various blocks being one or more units in length for expediting the formation of similar stretches of wall from different combinations of parts.

It is another object of my invention to improve building construction of this type in sundry details hereinafter pointed out. The preferred means by which I have accomplished my several objects are illustrated in the drawings and are hereinafter specifically described. That which I

believe to be new and desire to cover by Letters Patent is set forth in the claims.

In the drawings.—

Fig. 1 is a perspective view of a building structure made up of my improved blocks and associated parts, with some of the parts omitted and with the top portion raised slightly with respect to the bottom portion for clearness of illustration;

Fig. 2 is an outside face view of one of the blocks employed in the building of Fig. 1;

Fig. 3 is a cross sectional view taken at line 3—3 of Fig. 2;

Figs. 4, 5, 6 and 7 are face views of other blocks employed in the building of Fig. 1;

Fig. 8 is an end view of one of the roofing strips as employed in said building;

Fig. 9 is a face view of the corner portion of a structure built up from a plurality of the blocks;

Fig. 10 is a top plan view of the structure shown in Fig. 9;

Fig. 11 is a vertical sectional view taken at line 11—11 of Fig. 10;

Fig. 12 is an outside face view of the longest one of the blocks employed in the building of Fig. 1;

Figs. 13, 14, 15 and 16 are built-up structures by the employment of different sets of the various blocks for providing a stretch of parts corresponding to the length of the block shown in Fig. 12;

Fig. 17 is a view showing a combination of blocks for providing a stretch of parts of shorter length, and corresponding to the length of the block shown in Fig. 2;

Fig. 18 is a view similar to Fig. 17 but showing a different combination of parts; and

Fig. 19 is a top plan view of a structure in the form of an enclosure made up as shown from a plurality of similar blocks suitably locked together.

Referring now to the several figures of the drawings in which corresponding parts are indicated by the same reference characters, 20, 21, 22, 23, 24 and 25 indicate blocks of different form or size as employed in the building of Fig. 1. As is clearly shown in Figs. 2 and 3, the block 20 is substantially square in cross section, being provided with a groove 26 in its top face and a groove 27 in its bottom face, said grooves being centrally located so as to be disposed directly opposite to each other. At each end, the block 20 is cut away to provide a notch 28 of a length corresponding to the width of the block and of a depth corresponding to half of the thickness of the block.

The unnotched face portions at the ends of the block are provided with cross grooves 29 located at a distance from the end face of the block corresponding substantially to half of the thickness 5 of the block. The block 28 corresponds to one end portion of the block 20, being provided with top groove 26 and bottom groove 27, a notch 28 and a cross groove 29, the end at the left being square,—that is to say, at right angles to the 10 length of the block. Blocks 21 and 22 are square at both ends, the block 21 being of a length corresponding to its width and the block 22 having a length three times as great as its width. Each of the blocks 21 and 22 is provided with a top 15 groove 26 and a bottom groove 27. The block 24 is in the form of a wedge having a base of a length one and one-half times greater than its width and having a cross groove 30 across its oblique face substantially midway therealong, the 20 block 24 also having a top groove 26 and a bottom groove 27. The block 25 as shown in Fig. 12 is the same as the block 20 as shown in Fig. 2 except that the block 25 is of substantially double the length, as is shown by a comparison with 25 Fig. 13.

In the arrangement shown in Fig. 1, a plurality of the various blocks 20 to 25 are built up together to provide a building structure, the several tiers of blocks being connected together by means 30 of locking tabs 31 secured in the top grooves 26 of the several blocks and engaging the bottom grooves 27 of the next higher blocks. As is clearly shown in Fig. 1, the structure comprises also a window block 32 and a door block 33 which will 35 be hereinafter described, together with roofing strips 34 which are held in position upon the blocks 24 by means of locking tabs 31 mounted in the cross grooves 30 of the blocks 24 and extending into longitudinal grooves 35 in the bottom 40 faces of said strips.

As is best shown in Figs. 9, 10 and 11, in the arrangement shown each pair of notched blocks arranged in the same tier of blocks in crossed relationship to each other are locked together by 45 locking tabs 31, each of such locking tabs being mounted partially in a cross groove 29 and partially in a longitudinal groove 26 or 27, the aligned grooves in the top face in which one of the tabs 31 is mounted being at right angles to the aligned 50 grooves in the bottom face in which the other one of said locking tabs 31 is mounted. The dimensions of the parts are such that the locking tab mounted in the cross groove of one of said blocks holds the side face portion of the other block in tight engagement with the square end of the notch of said one block whereby the two blocks are secured together not only by the frictional engagement of the locking tabs in the 55 grooves but also by the frictional engagement of the side faces of the blocks with the square shoulders of the notches. By this arrangement the parts are held very firmly in position with respect to each other. At the same time, the parts 60 can be very readily disconnected by the application of a direct pull upon the parts for the removal of the locking tabs from the grooves.

As is clearly shown in Figs. 12, 13, 14 and 15, similar lengths of wall can be arranged readily 65 from different combinations of parts. Two of the blocks 20 can be employed to fill the space of a single block 25. Two of the blocks 23 and two of the blocks 21 can be employed together for filling the space of one block 20, as is shown 70 at the right in Figs. 13 and 14. Likewise two of

the blocks 23, two of the blocks 22, and one block 21 can be employed to fill the space of a single block 25, as is shown by a comparison of Figs. 12 and 15. For accomplishing this purpose, all of the blocks are given a length an integral number of times greater than the predetermined unit of length which in the construction as illustrated corresponds to the width of the block.

As is clearly shown in Figs. 1, 16 and 17, the window blocks 32 and the door blocks 33 are also dimensioned so as to cooperate to advantage with the unit system of the cooperating blocks. Each of the blocks 32—33 has a horizontal size corresponding to an integral number of units of length. 10 In the arrangement shown each of the blocks 32 and 33 has a horizontal size corresponding to two units of length. In the arrangement shown, the door block 33 has a vertical size corresponding to the height of three of the blocks 23, while the window block 32 has a vertical dimension corresponding to the height of two of said blocks 23. 15 As is clearly shown in Fig. 1, each of the blocks 32 and 33 is provided with a longitudinal groove 36 in its top face, a longitudinal groove 37 being 20 provided in its bottom face as is shown in Fig. 16.

In the arrangement as shown in Fig. 19, a plurality of the blocks 20a in one direction and 20b in the cross direction are built up together in a plurality of tiers to form wall portions in an 25 angular relation to each other for producing an enclosure, such enclosure in the arrangement shown being square in view of the fact that all of the blocks are of the same length as used in this 30 illustrative showing. Two locking tabs 31 are 35 employed at each corner between each two tiers of blocks. One of such two locking tabs at each corner is located in the longitudinal groove 26 of a block 20a and the top cross groove 29 of the interfitting block 20b of the same tier so as to 40 hold said interfitting block 20b from longitudinal movement with respect to said block 20a, and the other one of said two locking tabs at said corner is located in the longitudinal groove 27 of said 45 interfitting block 20b and the bottom cross groove 29 of the next higher block 20a so as to hold 50 said next higher block 20a from longitudinal movement. Inasmuch as the interlocking as specified is duplicated at all four corners, it will 55 be understood that the four wall portions are positively locked together. For effecting this locking, it is sufficient if each of the wall portions making up the structure have at least one full length block having the connections as specified with both of the adjacent wall portions, it being 60 permissible that the remaining blocks of each of the wall portions be broken up to provide wall openings for doors or windows, or for any other purpose.

By the use of my improved arrangement, a great variety of structures can be built up in accordance with the desire and whim of the builder. The arrangement is such that the parts fit readily together and are easily disconnected but at the same time have such a frictional grip upon each other as to cause the parts to remain readily in operative position. As is above set forth, with the parts skillfully arranged for providing the interlocking possible, a built-up structure can be provided of very substantial strength and stability.

As will be readily understood, the arrangement is such that the parts can be very readily produced. Wherever a groove is required at any given point, such groove is carried entirely 70 75

through the block so as to be capable of being very readily produced. I have found in practice that a machine of quite simple design can be employed for producing my improved blocks very rapidly and cheaply.

5 While I prefer to employ the form of parts as shown in my drawings and as above described, it is to be understood that my invention is not to be limited to the form as shown except so far as the narrower claims may be so limited in terms, it being understood that the claims cover not only the forms shown but their equivalents.

I claim:—

1. As a new article of manufacture, a building block cut away at one face at the end to provide a notch of a length corresponding to the width of the block, and having longitudinal grooves in its top and bottom faces, and having a groove transversely across the unnotched face portion 10 at a distance from the end face of the block corresponding substantially to half of the width of the block.

2. As a new article of manufacture, an elongated wooden building block rectangular in cross section and cut away at one face at the ends of the block to provide notches each of a length corresponding to the width of the block and of a depth corresponding to half of the vertical thickness of the block, and having narrow longitudinal 20 grooves in centered position in its top and bottom faces from end to end of the block, and having grooves transversely across the unnotched face portions of the block located at a distance from the end faces corresponding to half of the 30 width of the block.

3. A building block construction comprising in combination two blocks having notched end portions and arranged in rectangular relation to each other with their top faces in alignment and 40 with one of the side face portions of each of the blocks in engagement with a square shoulder portion of the notch of the other block, said two blocks having aligned grooves in their top faces and aligned grooves in their bottom faces in 45 crossed relationship to said first named grooves, and means for locking said two blocks together in frictional engagement with each other comprising a locking tab in the aligned grooves in the top faces and a second locking tab in the aligned 50 grooves in the bottom faces.

4. A building block construction comprising in combination two blocks having notched end portions and arranged in rectangular relation to each other with their top faces in alignment and 55 with one of the side face portions of each of the blocks in engagement with a square shoulder portion of the notch of the other block, said two blocks having aligned grooves in their top faces and aligned grooves in their bottom faces in 60 crossed relationship to said first named grooves, and means for locking said two blocks together in frictional engagement with each other comprising a locking tab in the aligned grooves in the top faces serving to hold one of said blocks in 65 frictional engagement with the shoulder portion of the notch of the other block and a second locking tab in the aligned grooves in the bottom faces serving to hold the other of said blocks in frictional engagement with the shoulder portion 70 of the notch of said one block.

5. A building block structure comprising in combination two blocks each notched at one of its longitudinal faces at one end and arranged in rectangular relation to each other with their top 75 faces in alignment and with one of the side face

portions of each of the blocks in engagement with a square shoulder portion of the notch of the other block, each of said blocks having longitudinal grooves in centered position in its top and bottom faces and having a cross groove in its unnotched longitudinal face in alignment with the longitudinal groove in the other block, and means for locking said two blocks together in frictional engagement with each other comprising a locking tab in the aligned grooves in the top faces and a second locking tab in the aligned 10 grooves in the bottom faces.

6. A building block construction comprising in combination three blocks each having longitudinal grooves in its top and bottom faces with one 15 face portion cut away at the end to provide a notch of a length corresponding to the width of the block and of a depth corresponding to half of the thickness of the block and having a cross groove in the unnotched face portion at a distance from the end face corresponding substantially to the distance of said longitudinal groove from the outer face of the block, one of said blocks being superposed on the second block and the third block being arranged in crossed relationship between said first and second blocks, and a locking tab in the longitudinal grooves of said superposed blocks and engaging the cross groove of the third block for holding said third block from longitudinal movement transversely of said 30 superposed blocks.

7. A building block construction comprising in combination four blocks each having longitudinal grooves in its top and bottom faces, with two of said blocks of the same length and cut away at both ends and the other two cut away at at least one end to provide notches in their faces of a length corresponding to the width of the block and of a depth corresponding to half of the thickness of the block, and having a cross groove 40 in the unnotched face portion at a distance from the end face corresponding substantially to the distance of said longitudinal grooves from the outer face of the block, said other two blocks being arranged in crossed relationship to one of 45 said double notched blocks at opposite ends thereof and the other double notched block being superposed on said three blocks, and locking tabs in the grooves between said superposed block and the other three blocks, with each of said 50 locking tabs engaging at least one longitudinal groove of one block and at least one cross groove of another block whereby said tabs hold each of said four blocks from longitudinal movement with respect to the other blocks.

8. A building block construction comprising in combination a plurality of blocks of similar cross sectional size and shape built up together in a plurality of tiers to form wall portions in angular relation to each other for producing an enclosure, each of the blocks at the corners of the structure being cut away at one face to provide notches by which the blocks are given interfitting relationship to each other, each of said blocks having longitudinal grooves in its top and bottom faces, and each of the notched blocks having a cross groove in its unnotched face at a distance from the end face of the block corresponding substantially to the distance of said longitudinal groove from the outer face of the block, and locking tabs engaging the grooves between each two tiers of blocks for locking the parts together, each of the wall portions of the structure having at least one full length block therein connected at each end with the next adjacent wall portion by 70 75

one of said locking tabs engaging at one end portion with a longitudinal groove in one of the blocks in said adjacent wall portion and engaging at its opposite end portion with the adjacent cross groove in said full length block whereby the several wall portions of the structure are positively locked together.

9. As a new article of manufacture, a building block in the form of a wedge having its end face positioned at right angles to its base, having a longitudinal groove in centered position in its bottom face, and having a cross groove in substantially perpendicular position with respect to the oblique face of the block at about the middle point therealong.

10. A building block construction comprising in combination two building blocks disposed opposite to each other at opposite ends of a building structure and each in the form of a wedge having its top face obliquely disposed and having a cross groove in substantially perpendicular position with respect to said oblique face at about the middle point therealong, locking tabs in said grooves and extending above the top faces of the blocks, and a thin strip having a longitudinal groove in its bottom face in position to engage said locking tabs and of a width corresponding substantially to the length of the oblique faces of said blocks.

NILS I. PAULSON. 15
